UNITED STATES PATENT OFFICE

JULIUS KAHN, OF YOUNGSTOWN, OHIO, ASSIGNOR TO TRUSCON STEEL COMPANY, OF YOUNGSTOWN, OHIO, A CORPORATION OF MICHIGAN

HIGHWAY GUARD

Application filed May 19, 1930. Serial No. 453,564.

The object of the present invention is to provide a strong guard structure that will resist and absorb the shock of an automobile travelling at high rate of speed, the structure being such that any parts which may become seriously damaged, can be readily replaced.

A further and important object of the invention is to provide a structure that will reflect the light from head lamps, without glare so that the guards are readily visible but not distracting.

In the embodiment disclosed:

Figure 1 is a view in elevation of a portion 15 of the preferred embodiment of the guard placed along a highway.

Figure 2 is a detail side elevation of a portion of one of the posts and the rods mounted thereon.

Figure 3 is a plan view.

Figure 4 is a plan view of the post.

Figure 5 is an edge view of one of the rod holding clips.

In the embodiment disclosed, a set of posts 25 6 is located along a highway at the place to be protected. Each of these posts is preferably made of galvanized sheet metal. Their general cross sectional form is a truncated V-shape, that is to say, there is a front flat wall 30 7 terminating in rearwardly extending flange portions 8 at substantially right angles thereto, and from these flange portions extend divergently disposed side walls 9 that terminate in parallel rear margins 10. Upon 35 the front walls 7 are fixed upper and lower clips 11, each clip being provided with two eyes 12. The clips may be riveted as shown at 13, or otherwise fastened in place.

Connecting adjacent posts are relatively 40 heavy guard rods 14, the end portions of which pass through clips and have nuts 15 threaded thereon. As a consequence it will be noted that the ends of the rods extending from one post to the adjacent post on one side 45 overlap the rods extending from the other post on the opposite side and their tension is in opposite directions. The end posts may be each suitably braced by an anchor rod 16 secured in one of the upper eyes with its lower end suitably fastened to an anchor or

"dead man" and having a turnbuckle 17 by which it can be placed under tension.

The structure produces a peculiarly effective guard in which the posts will withstand the shock of impacts and the rods are sufficiently heavy so that while they will yield slightly they too will withstand heavy impacts. Each part being placed under tension and all effectively tied together, the guard as a whole constitutes a unit of great strength. 55 The form and facing of the posts furthermore produces a series of angular reflecting surfaces which causes them to be noticeable at night but without glare.

From the foregoing it is thought that the 60 construction, operation and many advantages of the herein described invention will be apparent to those skilled in the art without further description and it will be understood that various changes in the size, shape, proportion and minor details of construction may be resorted to without departing from the spirit or sacrificing any of the advantages 65 of the invention.

What I claim, is:

1. A highway guard comprising a plurality of spaced channelled posts having angular rearwardly disposed light reflecting wing portions, forwardly extending clips rigidly secured to the closed front sides of the posts, 70 and substantially rigid line rods supported in front of the posts by the clips and having threaded ends, and means for tensioning the rods between the posts, said means being applied to the threaded ends of the rods and 75 bearing against the clips.

2. A highway guard comprising a series of spaced channelled metal posts having angular rearwardly extending wing portions and closed front portions, double tubular clips 80 rigidly secured to the closed front portions of the posts, and a series of substantially rigid line rods having threaded ends, extending between adjacent posts and supported in front of the posts by the clips, and nuts on the threaded ends of the rods bearing against the sides of the clips and rigidly tensioning said rods against the sides of the clips. 85

3. A highway guard comprising a series of rigid channelled posts having front web por- 100

tions, double tubular clips rigidly mounted on the front web portions of the posts, rigid guard rods extending between adjacent posts and supported on the front web portions of the posts by the clips, and means on the ends of the rods for uniting the posts and rods by rigidly tensioning the rods against the clips.

4. A highway guard having a series of rigid exteriorly channeled posts, clips rigidly secured to the front portions of the posts and a guard portion comprising a series of substantially rigid rods in front of the posts and supported thereon by the clips and presenting a substantially smooth front, and tensioning means on the ends of the rods for uniting the rods and posts into a substantially rigid structure by bearing against the sides of the tubular clips.

20 In testimony whereof, I affix my signature.
JULIUS KAHN.
